UNITED STATES PATENT OFFICE.

JOHN D. STEGEMAN, OF ALAMEDA, CALIFORNIA.

LUMBER-JACK.

1,012,286.

Specification of Letters Patent. Patented Dec. 19, 1911.

Application filed June 20, 1910. Serial No. 567,997.

To all whom it may concern:

Be it known that I, JOHN D. STEGEMAN, a citizen of the United States, residing at Alameda, in the county of Alameda and State of California, have invented certain new and useful Improvements in Lumber-Jacks, of which the following is a specification.

This invention relates to the subject of handling loads of lumber and other material in bulk and the principal object of the same is to provide novel load handling jacks for removing loads from cars and depositing the same on stands or piles or removing the loads from stands or piles and depositing the same on cars.

The improved jacks are primarily designed for use in connection with the load handling system that forms the subject matter of a co-pending application Serial No. 594,734 filed November 29, 1910, and which is a division of this application.

Figure 1 is a top plan view of one of the improved jacks. Fig. 2 is a vertical longitudinal sectional view thereof taken on the line 5—5, Fig. 1. Fig. 3 is a transverse vertical sectional view taken on the line 6—6, Fig. 2. Fig. 4 is a fragmentary vertical longitudinal sectional view taken on the line 7—7, Fig. 3. Fig. 5 is a top plan view of the forward truck of the improved jack. Fig. 6 is a view in side elevation, and Fig. 7 a view in end elevation of a rocker arm forming a part of the mechanism for adjusting the jacks. Fig. 8 is a plan view of a movable supporting plate carried by the jacks.

The improved jack which forms the subject-matter of this application, and which is designated generally by the numeral 5, comprises the body members 6 which are arranged in spaced parallel relation and are clipped or otherwise suitably fastened to the front and rear axles 7 and 8, each axle being provided with supporting wheels 9 and said wheels being preferably equipped with spaced peripheral flanges 10 which obviously prevent the jack tilting. Each axle has a sleeve 11 loosely mounted thereon one end of which is equipped with a ratchet wheel 12 and the other end with a cam 13.

A vertically movable platform 14 is arranged between body members 6, each end of said platform having a plate 15 fastened to the undersurface and from which an arm

16 depends. The lower ends of the arms 16 are provided with the bifurcations 17 in which the rollers 17^a are mounted. The bifurcations 17 straddle the cams 13 and the rollers rest on said cams so that when said cams are rotated the arms 16 are vertically adjusted to raise or lower the platform 14.

A rocking lever 18 is loosely mounted on the forward axle the upper end portion of which is provided with an outstanding pendant ear 19 which overhangs the ratchet wheel 12 of the forward axle and has a pawl 20 pivotally connected thereto. The lower portion of lever 18 is provided with a substantially right-angular extension 21 in which a socket 22 is formed for the reception of a hand lever 23. A coupling bar 24 pivotally connects the upper end of lever 18 with a rocking lever 25 that is loose on the rear axle and equipped with a pawl 26 similar to the lever 18 but which obviously is adapted for engagement with the ratchet 70 wheel 12 of the rear axle. The coupling bar 24 obviously causes the levers 18 and 25 to rock simultaneously, and it will be seen that 75 by rocking hand lever 23 a similar motion will be imparted to said levers 18 and 25 which causes their pawls 20 to engage with and rotate the ratchet wheels 12. The cams 13 and ratchet wheels 12 being fast in the 80 sleeves 11 it will be clear that rotation of the said ratchet wheels similarly actuates the said cams, so that arms 16 will adjust the platform 14. End plates 26 which connect the body members 6 prevent horizontal 85 movement of the platform 14.

Pawl 27 are provided for preventing reverse movement of the ratchet wheels 12, said pawls being pivotally mounted on stub shafts 28 that project laterally from one of the body members 6. Each pawl is provided with a crank arm 29, and said crank arms are pivotally connected by the coupler bar 30 to cause the pawls to simultaneously rock on the stub shafts 28. The crank arm of the 100 forward pawl is provided with a handle 31 that projects through a clearance opening 32 in the forward end plate 26. Said pawls 27 are thrown into engagement with ratchet wheels 12 by rocking handle 31 to lock said 105 wheels against reverse movement when the platform 14 is elevated. Hanger brackets 33 depend from one of the body members 6, one bracket being arranged in the rear of each axle. Said brackets receive the pawls 110

20 when the levers 18 and 25 are rocked rearward and thereby support the said levers when the platform 14 is lowered.

In use two of the jacks are used in connection with each load, the jacks being mounted on separate tracks and connected by means of the load. In transporting the load, it is obvious that one of the jacks may get ahead of the other jack, and if an attempt is made 10 to return the jacks to alinement, the friction of the lumber will exert a strain tending to overturn one of the jacks. To prevent this, the platform has a plate 34 fastened to its upper surface, said plate being provided 15 with transverse slots 35 adjacent the ends which register with recesses 36 formed in said platform. A movable plate 37 is seated on plate 34 and provided with pendent lugs 38 that enter said recesses and slots. Plate 20 37 receives the load, and it will be seen that the manner of connecting said plate with plate 34 and platform 14, permits plate 37 to have a lateral movement relative to the jack.

25 It will be seen that the improved jacks provide means whereby loads can be readily removed from cars and delivered to stands without being manually handled. And, as will be understood, the piles of lumber can 30 be readily removed from the stands by placing the jacks beneath the ends of the piles and then adjusting the jacks so that the platform 14 will lift the piles from the stands.

What I claim as my invention is:—

35 1. A jack comprising a body formed of spaced parallel members, an axle at each end of said body, a platform vertically adjustable between said members, a sleeve rotatable on each axle and carrying a cam and 40 a ratchet wheel, a rocking lever carrier by each axle, means for pivotally connecting said levers, pawls carried by said levers for engaging said ratchet wheels, means carried

by said members for preventing reverse movement of said ratchet wheels, means for 45 rocking said levers, and supporting means carried by said platform and engaging said cams.

2. A jack comprising a body, a platform vertically adjustable relative to said body, 50 axles for said body, wheels for said axles, sleeves loose on said axles, cams carried by said sleeves, arms depending from said platform and having bifurcated free ends straddling said cams, and manually operated 55 means carried by said axles for rotating said sleeves.

3. A jack comprising a body, axles therefor, wheels for said axles, sleeves loose on said axles, cams carried by said axles, a 60 platform adjustable relative to said body, arms depending from said platform and engaging said cams, and means carried by said axles for causing said cams to adjust said platform.

4. A jack comprising a body, axles for each end thereof, said body being formed of spaced parallel members, a platform vertically adjustable between said members, wheels for said axles, sleeves loose on said 70 axles and carrying cams, ratchets carried by said sleeves, levers loose on said axles, means carried by said levers for engaging said ratchets to rotate said sleeves, one of said levers being provided with a socket, a link 75 connection between said levers, a handle engaging said socket, arms carried by said platform and engaging said cams, and manually operated means for holding said ratchets against reverse movement.

In testimony whereof I affix my signature in presence of two witnesses.

JOHN D. STEGEMAN.
